PORTABLE OVERHEAD JACK

Hugh K. Christie, Harvey, Ill., assignor to Whiting Corporation, Harvey, Ill., a corporation of Illinois

Application September 22, 1943, Serial No. 503,374

4 Claims. (Cl. 212—14)

The present invention relates generally to portable overhead jacks. More particularly the invention relates to that type of portable overhead jack which is adapted to travel back and forth along a track in the form of a pair of laterally spaced rails and as its principal parts comprises a gantry type supporting structure, a wheel equipped truck on the bridge of the supporting structure, and raising and lowering mechanism on the truck.

One object of the invention is to provide a portable overhead jack of this type which has special utility in connection with dismantling the trucks of Diesel electric locomotives after removal of the trucks from the locomotive chassis and is characterized by simplicity and cheapness of construction as well as high efficiency, ease of operation and durability.

Another object of the invention is to provide a portable overhead jack in which the raising and lowering mechanism on the truck comprises a vertically extending screw shaft and motor driven gearing for shifting the shaft upwards and downwards.

A further object of the invention is to provide a portable overhead jack of the last mentioned character in which the vertically extending screw shaft of the raising and lowering mechanism embodies a hook at its lower end for attachment to the load and is supported and housed in a simple and novel manner.

A still further object of the invention is to provide a portable overhead jack which is generally of new and improved construction and is an improvement upon, and has certain advantages over, previously designed jacks of the same general character.

Other objects of the invention and the various advantages and characteristics of the present portable overhead jack will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a side view of a portable overhead jack embodying the invention;

Figure 2 is an end view, certain parts being broken away for illustrative purposes;

Figure 3 is an enlarged view of the wheel

equipped truck, parts being shown in side elevation and other parts being shown in section;

Figure 4 is an enlarged vertical transverse section taken on the line 4—4 of Figure 1 and showing the truck in end elevation;

Figure 5 is a horizontal section of the housing which forms a part of the frame of the truck and serves to enclose the gearing for shifting the screw shaft upwards and downwards;

Figure 6 is a vertical section taken on the line 6—6 of Figure 5 and illustrating in detail the manner in which the screw shaft is supported and housed; and

Figure 7 is a horizontal section taken on the line 7—7 of Figure 6 and showing the construction and design of the means for holding the screw shaft against rotation while at the same time permitting the shaft to slide vertically.

The overhead jack which is shown in the drawings constitutes the preferred form or embodiment of the invention. It is portable and has special utility in dismantling the trucks of Diesel type locomotives after removal of the trucks from the locomotive chassis. As its main or principal parts the jack comprises a gantry type supporting structure 8, a truck 9, and load raising and lowering mechanism 10.

The supporting structure 8 is adapted to travel back and forth along a track 11 and serves as a supporting medium for the truck 9. The track 11, as shown in Figure 1, comprises a pair of laterally spaced rails 12 which are disposed outwards of, and in straddled relation with, a standard gauge release or service track 13. The latter is adapted to receive the locomotive trucks after removal or disconnection thereof from the Diesel electric locomotive being serviced. The rails 12 of the track 11 are preferably spaced equidistantly from the rails constituting the track 13.

The supporting structure 8 consists of a horizontal bridge 14 and a plurality of upstanding legs 15 at the ends of the bridge. The length of the bridge corresponds substantially to the width of the space between the rails 11 constituting the track 12. It is held or maintained in elevated relation by the legs 15 and consists of a pair of parallel, laterally spaced, coterminous channel beams 16. The latter are arranged so that the webs thereof extend vertically and their flanges extend outwards. The ends of the channel beams 16 are cross connected by a pair of vertically extending plates 17 and a pair of horizontal plates 18. The vertical plates fit against, and are welded to, the end edges of

the webs of the channel beams 16. The hori-

zontal plates 18 underlie and are welded to the end portions of the lower flanges of the beams 16. The legs 15 are four in number and are arranged so that there are two at each end of the bridge 14. Preferably the legs are formed of pipe or tubular stock. The two legs at each end of the bridge are downwardly divergent as shown in Figure 2. The upper ends of the legs are welded or otherwise fixedly secured to the horizontal plates 18 which, as previously pointed out, operate in conjunction with the vertical plates 17 to cross connect the channel beams 16 forming the bridge 14 of the gantry type supporting structure 8. Substantially vertical gusset plates 19 extend between, and are welded to, the upper ends of the legs 15 and the inner portions of the horizontal plates 18 and serve to brace the legs. In addition to the bridge 14 and the legs 15 the supporting structure 8 comprises four wheels 20. These wheels are mounted on, and adapted to travel along, the rails 12 of the track 11 and are arranged so that one is located at the lower end of each of the legs 15. Each of the wheels is provided with a central horizontally arranged axle 21 which is journaled in a journal box 22. The boxes 22 are associated respectively with, and are welded or otherwise fixedly secured to the lower ends of, the legs 15. A horizontally extending pipe type brace 23 extends between, and is fixedly secured to each pair of journal boxes 22, as shown in Figure 2. The wheels 20 permit the gantry type supporting structure 8 to be shifted in either direction along the track 11. If desired the axles of certain of the wheels may be provided with ratchet type levers 24 for use in manually propelling the supporting structure with respect to the track 11.

The truck 9 is horizontally elongated and serves as a mobile unit or medium for supporting the raising and lowering mechanism 10. It extends lengthwise of, and is adapted to travel back and forth along, the bridge 14 of the gantry type supporting structure 8, and comprises a frame 25, a pair of coaxial supporting wheels 26 at one end of the frame, and a pair of coaxial supporting wheels 27 at the other end of the frame. The frame 25 is preferably in the form of a one-piece metallic casting and consists of an elongated central part 28, a pair of laterally spaced, longitudinally extending arms 29 at one end of the central part, and a pair of laterally spaced, longitudinally extending arms 30 at the other end of said central part of the frame. As shown in Figures 5 and 6 the central part 28 of the frame is shaped so that it defines an open top housing and consists of a bottom wall and an upstanding rectangular side wall. The open top of the housing that is defined by the central part 28 of the truck frame 25 is closed by a rectangular cover plate 31 which rests upon, and is removably secured to, an outwardly extending marginal flange at the upper margin of the upper rectangular side wall of said central part 28. When the cover plate 31 is released access may be had to the interior of the housing. The arms 29 extend horizontally and project outwards in one direction from the housing defining central part of the truck frame 25. The other arms, i. e., the arms 30, extend horizontally and project outwards in the opposite direction from the central part 28 of the truck. Preferably the inner ends of the arms 29 are extended inwards and join the inner ends of the arms 30. The outer ends of the arms 29 are shaped to define a pair of coaxial bearings 32. A horizontal axle 33 extends through, and is

journalled in, the bearings 32. The supporting wheels 26 are keyed or otherwise fixedly secured to the ends of the axle 33 and are adapted to travel on the upper flanges of the channel beams 16 of the bridge 14, as shown in Figure 4. The inner portions of the wheels 26 are provided with radially extending annular flanges 26a and these coact with the upper inner corners of the channel beams 16 to hold the truck 9 against side-wise or lateral displacement with respect to the bridge 14 of the gantry type supporting structure 8. The outer ends of the arms 30 are provided with a pair of coaxial bearings 34 and these serve rotatably to support a horizontal axle 35. The supporting wheels 27 are mounted on the ends of the axle 35 and, like the wheels 26, are adapted to travel on the upper flanges of the channel beams 16. The inner portions of the wheels 27 are provided with radially extending annular flanges 27a and these coact with the upper inner corners of the channel beams 16 to prevent lateral displacement of the truck 9 with respect to the bridge. The axles 33 and 35 extend transversely of the channel beams 16. The supporting wheels 26 and 27 permit the truck 9 to travel back and forth along the bridge 16. In order to facilitate shift of the truck 9 along the bridge manually manipulable gearing 36 is provided. This gearing comprises a pinion 37 and a gear 38. The pinion 37 is mounted on a horizontally extending shaft 39 which overlies, and is disposed in parallel relation with, the axle 33 and is journaled in a pair of bearings 40. The latter, as shown in Figure 4, are connected to, and project upwards from, the bearings 32 for the axle 33. The gear 38 meshes with the pinion 37 (see Figure 3). It is mounted on the central portion of the axle 33 and is disposed between the bearings 32 at the outer ends of the arms 29 of the truck frame 25. In addition to the pinion 37 and the gear 38 the gearing 36 comprises a wheel 41 and an endless chain 42. The wheel 41 is fixedly secured to one end of the pinion carrying shaft 39 and has a circumferentially grooved periphery. The chain 42 extends around, and depends from, the wheel 41 as shown in Figure 1 and is of such length that the bottom portion thereof may be readily grasped by the operator of the jack. By pulling downwards on one of the side reaches of the chain the wheel 41 is caused to rotate in one direction and operates through the medium of the pinion 37 and the gear 38 to propel the truck 9 in one direction along the bridge 14. Downward pulling of the other side reach of the chain results in reverse rotation of the wheel 41 and shift or propulsion of the truck in the opposite direction along the bridge. By manipulating the chain the operator of the jack may propel the truck back and forth along the bridge.

The load raising and lowering mechanism 10 comprises a vertically extending screw shaft 43 and gearing 44 for shifting the shaft upwards and downwards. The screw shaft extends through a circular hole 45 in the central portion of the bottom wheel of the central part 28 of the truck frame 25, and is provided at its lower end with a hook 46. The hook is adapted to be attached to the load by way of chains or the like and has at its upper end a lug 47 which fits within a fork 48 at the lower end of the screw shaft and is pivotally connected thereto by way of a horizontal pivot pin 49. The cover plate 31 is provided at its central portion with a hub-like part 50 through which the screw shaft 43 extends. As shown in Figure 6, the hub-like part 50 is in

coaxial relation with the hole 45 in the bottom wheel of the central part 28 of the truck frame 25 and is of slightly greater diameter. An upstanding tube 51 serves to house the upper end of the screw shaft 43. The lower end of this tube is provided with a radial outwardly extending flange 52 which rests upon, and is bolted to, the upper end of the hub-like part 50 on the central portion of the cover plate 31. The upper end of the tube 51 is closed by a disc-like cover 53. The tube 51 is of sufficient length to accommodate the screw shaft 43 when it is raised to its fullest extent with respect to the truck 9. A cross pin 54 at the upper end of the screw shaft serves to hold the shaft against rotation while at the same time permitting the shaft to slide vertically with respect to the tube 51. One end of this pin fits slidably in a vertical internal groove 55 in the tube and the other end of the pin extends through a vertical slot 56 in the tube (see Figure 7). The slot and groove are positioned one diametrically opposite the other. A sleeve-like nut 57 surrounds the screw shaft and is disposed in the housing which is formed by the central part 28 of the truck frame 25. This nut is rotatable relatively to the screw shaft and is confined against vertical displacement with respect to the frame of the truck. The lower end of the sleeve rests on a roller type thrust bearing 58 which in turn rests upon, and is supported by, the portion of the bottom wall of the central part 28 that defines the hole 45. The upper end of the nut is journaled in the hub-like part 50 on the central portion of the cover plate 31. The central portion of the nut is provided with a radially extending flange 59 and this, as shown in Figure 6, underlies the lower end of the hub-like part 50 and prevents upward displacement of the nut with respect to the central part 28 of the truck frame 25. When the nut 57 is turned or rotated in one direction the screw shaft 43 is caused to slide upwards. Reverse rotation of the nut results in lowering of the shaft.

The gearing 44 for shifting the screw shaft upwards and downwards is irreversible in character and comprises a worm 60 and a worm wheel 61. The worm is keyed to the central portion of a horizontally extending shaft 62 and is disposed in the housing that is defined by the central part 28 of the truck frame 25. The ends of the shaft 62 are journaled in bearings 63 in the side parts of the upstanding side wall of the central frame part 28. The worm wheel 61 surrounds and is fixedly secured to the lower end of the sleeve-like nut 57 and meshes with the worm 60. When the worm 60 is rotated in one direction it so drives the worm wheel 61 and the nut 57 as to effect vertical displacement of the screw shaft in one direction. Reverse drive of the worm 60 results in reverse rotation of the worm gear and nut and resultant vertical displacement of the screw shaft in the opposite direction. A reversible electric motor 64 serves to drive the worm 60 in either direction. This motor is mounted on a bed plate 65 over the axle 35 and is operatively connected to the shaft 62 by way of a pulley and belt connection 66. As shown in Figure 3, the bed plate 65 is supported by a bracket structure 67 on the outer ends of the arms 30 of the truck frame 25. The pulley and belt connection 66 comprises a pulley 68 on one end of the armature shaft of the motor 64, a pulley 69 on one end of the shaft 66, and an endless belt 70 around the two pulleys. The electric motor is supplied with current in any suitable

manner and is controlled by a push button control unit (not shown). Such unit is preferably located within reach of the operator of the jack. An upper limit switch 71 and a lower limit switch 72 serve automatically to stop the electric motor when the screw shaft is raised or lowered to its fullest extent. The switch 71 is located at the upper end of the tube 51 and is controlled by the end of the cross pin 54 that projects through the vertical slot 56 in the tube. The lower switch 72 is located adjacent the lower end of the tube and is also controlled by said end of the cross pin. When it is desired to use the jack to dismantle a Diesel electric locomotive truck after disconnection of the truck from the locomotive chassis the truck is rolled onto the release or service track 13. The latter, as previously pointed out, is straddled by the track 11 for the portable overhead jack. After the locomotive truck is rolled onto the track 13 the jack as a whole is propelled into overlying relation with the truck by manipulation of the levers 24. When the jack is properly spotted or located with respect to the truck the electric motor 64 is actuated so as to lower the screw shaft 43. As soon as the shaft is lowered to the desired extent the motor is stopped. Thereafter the hook 46 is attached to the locomotive truck by chains, cables or the like. After attachment of the hook to the truck the electric motor 64 is reversely driven so as to effect raising of the screw shaft together with the truck. If it is desired to shift the locomotive truck laterally with respect to the track 13 the truck is propelled along the bridge 14 of the gantry type supporting structure 8 by manipulating the chain 42. The screw shaft may be used to remove a motor from the locomotive truck. It also may be used to lift the locomotive truck in connection with removal of the wheels therefrom.

40 The herein described portable overhead jack effectively and efficiently fulfills its intended purpose and is characterized by simplicity and cheapness of design or construction and also ease of operation.

45 Whereas the jack has been described as being expressly designed for use in connection with dismantling trucks that have been removed from Diesel locomotives it is understood that it may be used in many other capacities. It is also to be understood that the invention is not to be restricted to the details set forth since these may be modified within the scope of the appended claims without departing from the spirit and scope of the invention.

55 Having thus described the invention what I claim as new and desire to secure by Letters Patent is:

1. An overhead jack comprising a gantry type supporting structure having an elongated horizontal bridge at the top thereof, a truck mounted on the bridge to travel in either direction therealong and provided with a housing, a vertical tube connected to, and extending upwards from, the upper portion of the housing, a vertical screw shaft extending through the housing and into the tube, mounted to move vertically and having the lower end thereof exposed and provided with means for attachment to a load, means between the upper end of the shaft and the tube for holding the screw shaft against rotation while at the same time permitting it to move vertically, and mechanism for raising and lowering the screw shaft, embodying a rotatable nut mounted on the screw shaft and confined in the housing against axial displacement relatively to

the truck, a worm wheel in the housing extending around, and connected fixedly to, the nut, and a worm in said housing in mesh with the worm wheel.

2. An overhead jack comprising a gantry type supporting structure having an elongated horizontal bridge at the top thereof, a truck mounted on the bridge to travel in either direction therealong, a vertical screw shaft carried by the truck to move vertically and provided at the lower end thereof with means for attachment to a load, means for holding the screw shaft against rotation while at the same time permitting it to move vertically, and mechanism on the truck for raising and lowering the screw shaft, embodying a rotatable nut mounted on the screw shaft and confined against axial displacement relatively to the truck, a worm wheel extending around, and connected fixedly to, the nut, a worm in mesh with the worm wheel, and a reversible electric motor connected to drive the worm.

3. An overhead jack comprising a gantry type supporting structure consisting of a pair of laterally spaced upstanding legs with track engaging wheels at their lower ends and an elongated horizontal bridge extending between the upperends of the legs and in the form of a pair of parallel laterally spaced channel beams arranged so that the webs thereof extend vertically, a truck consisting of a cast metal frame elongated lengthwise of the bridge and embodying a housing forming central part and two pairs of horizontal laterally spaced arms connected to, and extending

outwards in opposite directions from, said central part, and wheels mounted rotatably adjacent the outer ends of the arms, resting on the upper flanges of the beams and adapted to permit the truck to travel in either direction along the bridge, a vertical screw shaft provided at its lower end with means for attachment to a load and carried by the truck so that it is disposed between the channel beams and is movable vertically, and gearing on the truck for raising and lowering the screw shaft.

4. An overhead jack comprising a gantry type supporting structure having an elongated horizontal bridge at the top thereof, a truck mounted on the bridge to travel in either direction therealong and provided with a housing, a vertical tube connected to, and extending upwardly from, the upper portion of the housing, a vertical screw shaft extending through the housing and into the tube, mounted to move vertically and having the lower end thereof exposed and provided with means for attachment to a load, means between the upper end of the shaft and the tube for holding the shaft against rotation while at the same time permitting it to move vertically, and mechanism for raising and lowering the screw shaft, embodying a rotatable nut in the housing extending around the screw shaft and confined in the housing against vertical displacement relatively to the truck, and gearing in said housing for rotating the nut in either direction.

HUGH K. CHRISTIE.
